CLAIM

The ornamental design for a storage container for thermometer, as shown and described.

DESCRIPTION

FIG. 1 is a top front side perspective view of the storage container for thermometer of the present invention.

FIG. 2 is a front view of the storage container for thermometer shown in FIG. 1.

FIG. 3 is a rear view of the storage container for thermometer shown in FIG. 1.

FIG. 4 is a right side view of the storage container for thermometer shown in FIG. 1.

FIG. 5 is a left side view of the storage container for thermometer shown in FIG. 1.

FIG. 6 is a top view of the storage container for thermometer shown in FIG. 1; and,

FIG. 7 is a bottom view of the storage container for thermometer shown in FIG. 1.

The features depicted in broken lines form no part of the claimed design.

1 Claim, 7 Drawing Sheets
